DESIGN FOR A BOTTLE

William R. Kohl, New York, N. Y., assignor to Carr-Lowrey Glass Co., Baltimore, Md.

Application April 22, 1938, Serial No. 76,704

Term of patent 14 years

To all whom it may concern:

Be it known that I, William R. Kohl, a citizen of the United States, residing at New York, in the county of New York and State of New York, have invented a new, original, and ornamental Design for a Bottle, of which the following is a specification, reference being had to the accompanying drawing, forming part thereof.

I claim:

The ornamental design for a bottle, as shown.

WILLIAM R. KOHL.
